DESIGN FOR A TIME STAMP

Joseph W. Faris, Cincinnati, Ohio, assignor to
The Cincinnati Time Recorder Company, Cincinnati, Ohio, a corporation of Ohio

Application June 3, 1938, Serial No. 77,552

Term of patent 14 years

To all whom it may concern:

Be it known that I, Joseph W. Faris, a citizen of the United States and a resident of Cincinnati, in the county of Hamilton and State of Ohio, have invented a new, original, and ornamental Design for a Time Stamp, of which the following is a specification, reference being had to the accompanying drawing, forming part thereof.

In the drawing:—

The figure is a front perspective view of a time stamp showing my new design, the back thereof

being contoured like the front and the side not shown bearing substantially the same appearance as the end shown.

The novel features of the design consist in the shape, proportion and contours of the housing for the time stamp mechanism, substantially as illustrated in the drawing.

I claim:—

The ornamental design for a time stamp, substantially as shown and described.

JOSEPH W. FARIS.
